UNITED STATES PATENT OFFICE.

CHARLES ZABEL, OF CORAOPOLIS, PENNSYLVANIA, ASSIGNOR, BY MESNE ASSIGNMENTS, TO TOSCA ZABEL, OF FEURA BUSH, NEW YORK.

TOY PILE DRIVER.

Application filed June 15, 1926. Serial No. 116,113.

The present invention relates to mechanical toys, and more particularly to a toy which operates in simulation of a pile driver or similar piece of machinery.

5 The invention has for its principal object to provide a toy which may be cheaply constructed, which may be packed in a relatively small space, and which has a considerable amount of action so as to make it fascinating and pleasing as a toy.

10 The invention may be readily understood by reference to the accompanying drawings illustrating preferred embodiments of my invention.

15 In the drawings:

Figure 1 is a side elevation of one form of toy;

Figure 2 is a top plan view of the toy shown in Figure 1;

20 Figure 3 is a detail perspective view illustrating the intermittent gearing by means of which the toy is rendered effective;

Figure 4 is a side elevation of a slightly modified form of the invention;

25 Figure 5 is a top plan view of the toy shown in Figure 4;

Figures 6 and 7 are detail diagrammatic views illustrating the position of respective parts in another form of intermittent gear-

30 ing.

Figure 8 is a somewhat diagrammatic view of another form of intermittent drive for the drum.

Referring first to the construction shown 35 in Figures 1 to 3 inclusive of the drawings, 2 designates a base on which is secured a spring motor 3 of familiar type and on which are upright members 4 that supports a shaft 5 on which a winding drum 6 is secured.

40 Detachably set on the base 2 is an upright frame 7 having vertical legs 8 and inclined legs 9. The vertical legs 8 have turned-in foot portions that engage under eye members 10 secured to the base. The inclined legs 9, which are connected by a cross member 9^a are secured to the base by means of cleats 11 carried on the base 2 and under which the crossbar 9^a is hooked, as shown in Figures 1 and 2. The frame 7 is preferably formed of a continuous piece of relatively stiff wire. Set on the top of the frame and secured thereto is a cross-piece 12 on which is supported a pulley or sheave 13.

55 Slidably vertically on the parallel vertical legs 8 is a block 14 having notched ends 15 which straddle the respective legs 8 so as to slidably retain the block on the legs. This block is supposed to imitate the hammer of a pile driver and is arranged to be raised and lowered by means of a cord 16 secured thereto, this cord passing over the sheave 13 and having its end secured to the drum 6.

60 For operating the block 14, means is provided for intermittently driving and releasing the drum 6. In the construction shown in Figures 1 and 2 this means includes a mutilated gear wheel 17 driven by the spring motor 3. This mutilated gear is arranged to cooperate with a pinion 18 on the shaft 5 70 which carries the drum 6.

65 In the operation of the toy the spring motor 3, or any other suitable driving means which may be substituted therefore, continuously revolves the mutilated gear 17. 75 When the toothed segments of this gear engage the pinion 18, the drum 6 is rotated several times to wind up the cord 16 and raise the weight or block 14. When the toothed portion of the mutilated gear 17 passes out of engagement with pinion 5, the weight of the block 14 causes the block to drop, unwinding the cord from the drum 6. Upon further rotation of the mutilated gear 17 the drum 6 will again be rotated to lift the 80 block 14 and in this manner the block 14 will be raised and dropped in simulation of the action of a pile driver or similar piece of mechanism, and inasmuch as the action is entirely automatic and mechanical, it 85 affords considerable entertainment as a toy.

90 By having the stand 7 detachably secured to the base 2, it can be readily taken down and set in the broken line position indicated in Figure 1, so that the toy can be conveniently put in a box of relatively small size. At the same time the construction is so simple that anyone can get up the stand upon unpacking the toy and set the toy in operation.

95 In the arrangement shown in Figures 4 to 7 inclusive the general arrangement is similar to that hereinbefore described and similar reference numerals have been used to designate the corresponding parts. The 100 form of the invention illustrated in Figures 4 to 7 inclusive contains a different arrangement of gearing for intermittently trans-

mitting motion to the drum 6. In this form of the invention I have also illustrated an added feature which can be used equally well with the arrangement shown in Figures 5 1 to 3 inclusive.

Therefore instead of using a mutilated gear, as shown in Figure 3, I have illustrated the motor 3 as driving a pinion 20 having a pair of pins or lugs 21 thereon at 10 diametrically opposite points.

The pinion 18 on the drum shaft 5 meshes with a continuous gear wheel 22 carried on a shaft 23 in the support 4. The shaft 23 is slightly out of line with the center of the pinion 20, as best shown in Figures 6 and 7. As the gear wheel 20 revolves, one of the pins 21 will come into contact with a lug 24 on the face of the pinion 22, and rotate the pinion 22 through a limited arc until 20 the difference in the alinement of the shafts shall cause the co-engaging pins or lugs to move out of engagement with each other. As soon as one of the pins 21, for instance, has moved past the pin 24, the weight 14 25 will drop by gravity. By the time the weight 14 has reached the lowermost point of its movement the next pin 21 will pick up the lug or pin 24 of the pinion 22 and repeat the operation of lifting the weight 30 and letting it drop. The particular advantage of this arrangement over that shown in Figure 3 is that the gears themselves will always remain in mesh, whereas in the construction shown in Figure 3 the 35 gears are only intermittently in mesh, and if they do not happen to always fall into proper engagement with each other the toy will have a tendency to stick and the life of the gear 18 will be short. The arrangement 40 shown in Figures 4 and 5 can be manufactured more cheaply and the toy assembled with greater facility due to the fact that less accuracy is required.

In order to add further to the action and 45 attractiveness of the toy, a representation of a boiler with an operator standing adjacent it may be provided. In Figures 4 and 5, 25 is a sheet of metal secured to the base 2 adjacent the motor 3 and which is shaped 50 and decorated to represent a boiler. Pictured on one side of the plate 25 is a man and this picture of the man, designated 26 is provided with a movable arm 27 pivoted to the plate 25 at 28. The free end of this 55 arm is pivotally connected by a loose pivot to one end of a lever 29 pivotally supported on the boiler 25 at 30. The end of this lever projects into the path of travel of the pins 21. As the gear 20 revolves the pins 21 will 60 rock the lever 29, giving a corresponding movement to the arm of the figure. This arrangement gives the appearance of an operator standing beside a boiler operating a control lever.

55 In the driving means illustrated in Fig-

ure 8, the drum 32 is mounted in the supporting frame 33 on a shaft 34 which has a pinion 35 thereon corresponding to the pinion 18, shown in Figures 2 and 5. Meshing with this pinion is a gear wheel 36 having a pin 37 projecting out from the face thereof. The diameter of the pinion 36 is considerably greater than the diameter of the pinion 35 so that the pinion 35 will be revolved several times upon the partial revolution of the pinion 36. The pinion 36 is intermittently driven by successive engagement with the arms 39 of a continuously rotated member 40 on the motor driven shaft 41.

In the operation of the arrangement thus provided the arms 39 will engage the pin 37 on the gear 36 and thus rotate this gear through a limited arc, after which the pin will move out of engagement with the radial face of the gear, allowing the weight to drop, and allowing the gear 36 to rotate in the opposite direction by reason of the dropping of this weight. By the time the weight has reached its lowermost position the next arm 39 will engage the pin 37 and repeat the operation. This arrangement also has the advantage that the gears are always in mesh. This arrangement has the advantage of requiring less accuracy in the setting of the parts than is required by either of the other two forms illustrated, so that it can be more easily assembled. The number of arms 39 may be varied according to the rapidity with which it is desired to raise and lower the member 14 and according to the distance which it is necessary to raise and lower this weight.

While I have illustrated certain preferred embodiments of my invention it will be understood that the invention may be otherwise embodied, and that various changes and modifications may be made in the construction thereof and the particular arrangement of parts within the contemplation of the spirit of my invention and under the scope of the appended claims.

I claim:

1. A mechanical toy including a base member, a rotatable drum carried on the base member, a driving motor on the base member, means operatively interposed between the driving motor and the drum for intermittently driving the latter, a vertical support on the base, a weight member slidably on the vertical support and a cord connecting the weight and the drum, guiding means for the cord being provided adjacent the upper end of the support.

2. A mechanical toy comprising a base member, a vertical support on the base member, a weight member slidably guided on the support, a cord connected with the weight member, means on the support at the top thereof over which the cord is guided, a

drum to which the cord is attached, a driving motor on the base, and an interrupted gearing operatively interposed between the drum and the motor.

5 3. A mechanical toy comprising a base member, a vertical support on the base member, a weight member slidably guided on the support, a cord connected with the weight member, means on the support at the top thereof over which the cord is guided, a drum to which the cord is attached, a motor on the base, and intermittent gearing for driving the drum from the motor.

15 4. A toy comprising a base member, a tower removably secured to the base member, said tower being formed of a single piece of wire having upright legs and inclined legs, cleat members on the base and eye members on the base to which the tower structure is removably secured, a spreader at the top of the tower structure having cord guiding means thereon, a weight element slidably guided between the vertical legs of the tower, a cord attached to the weight and passing over the cord guiding means, and means on the base for intermittently winding up and releasing the cord whereby the weight is caused to be raised

30 and dropped.

5 5. A mechanical toy representing a miniature pile driver having a base member and an upright member, a weight slidable in the upright member, a cord for raising the upright member, a drum supported on the base member to which the cord is attached, and means on the base member for intermit-

tently rotating the drum in one direction and then releasing it.

6. A mechanical toy representing a miniature pile driver having a base member and an upright member, a weight slideable in the upright member, a cord for raising the upright member, a drum supported on the base member to which the cord is attached, and means on the base member for intermittently rotating the drum in one direction and then releasing it, said means including a motor, and an intermittent gearing between the motor and the drum.

15 7. In a mechanical toy having a weight member which is raised and lowered through an intermittent gear mechanism, a lever arranged to be rocked by the intermittent gear mechanism, and a toy figure having a movable arm connected with the lever.

8. In a mechanical toy having a base member and a weight which is arranged to be raised and lowered by means of a motor on the base member, a lever arranged to be operated by the motor along with the weight and a figure mounted on the base having a movable arm which is connected with the lever.

15 9. A toy representing a miniature pile driver or the like having a base member, an intermittent gear mechanism mounted on the base, and a weight supported above the base operatively connected with intermittent gear mechanism whereby the weight is raised and lowered upon the operation thereof.

In testimony whereof I have hereunto set my hand.

CHARLES ZABEL.
